UNITED STATES PATENT OFFICE.

ALONZO G. KINYON, OF ALLENTOWN, PENNSYLVANIA, ASSIGNOR TO FULLER-LE-HIGH COMPANY, A CORPORATION OF PENNSYLVANIA.

FLUENT PULVERIZED FUEL.

Application filed November 23, 1920. Serial No. 426,016.

To all whom it may concern:

Be it known that I, ALONZO G. KINYON, a citizen of the United States, residing at Allentown, in the county of Lehigh, State of Pennsylvania, have invented certain new and useful Improvements in Fluent Pulverized Fuel; and I do hereby declare the following to be a full, clear, and exact description of the invention, such as will enable others skilled in the art to which it appertains to make and use the same.

This invention relates to a new fuel consisting primarily of coal in a state of fine sub-division and a relatively small amount of air intimately mixed therewith. This novel fuel is distinctive in that it is sluggishly fluent and in that a mass of the fuel at rest in a container will settle gradually, giving up its air content to the surrounding atmosphere slowly. Such a fuel is of great value by reason of the ease, simplicity, and economy with which it may be conveyed from a supply point to one or more points of use; furthermore, under certain conditions of use, the presence of the air in the fuel and its intimate mixture with the fuel particles may be utilized to advantage in effecting quick and complete combustion of the fuel.

Such a fuel is produced by injecting air under pressure into a body of pulverized coal under such conditions that the air becomes finely sub-divided and intimately mixed with the coal particles. The total volume of the air so injected into the pulverized coal may be several times the volume of the coal; experience indicates that the injection of six or eight units of volume of air to each unit of volume of pulverized coal produces very good results. The fuel thus produced is in a sluggishly fluent, or semi-fluid state, so that it offers relatively little frictional resistance to flow in a conduit and therefore may be made to flow through a long conduit by the application of mechanical pressure on the material at one end of the conduit. The presence of the air which is entrapped under pressure within the interstices of the mass, reduces the normal friction between the particles to such a degree that a mass of the material when unconfined possesses substantially no angle of repose and will flow freely over any surface upon which it may be

poured. If the fuel be poured into a barrel or other container and the barrel be tilted slightly on its edge, the fuel will surge back and forth. The end of a bar of a piece of wood may be inserted into the fuel in the container and moved back and forth therein with but little resistance to its movement on account of the fluid character of the fuel. In this state of rest of the fuel in the barrel, there would be slow settling of the fuel as the air particles in the fuel rose to and escaped from the surface of the fuel, but this settling is not rapid enough to have any substantial detrimental effect in the utilization of the fuel, particularly as it occurs only when the fuel is exposed to atmospheric pressure.

By reason of this semi-fluid condition and the fact that a body of the new fuel at rest will settle but slowly, the new fuel is sharply distinguished from those mixtures of air and pulverized coal which have been commonly employed heretofore in which the volume of the air is many times the volume of coal and the coal particles are in suspension in the air. Such mixtures are usually formed to permit of conveying the coal by means of a moving current of air, and when such mixtures are brought to rest, the coal particles drop by gravity practically immediately and collect in a mass at the bottom of the receptacle into which the mixture is brought to rest.

A mixture in which the particles of coal are held in suspension in a relatively large volume of air is explosive in its nature, and care must be exercised that it is not accidentally ignited. The present fuel is not an explosive mixture and may be handled with safety under all conditions. Furthermore, since the fuel contains a relatively small amount of entrapped air as compared with the amount present in mixtures in which the coal particles are conveyed in suspension, it may be discharged from distributing conduits directly without requiring the use of apparatus such as cyclone separators to remove the air. The fuel is also free from dust and is therefore clean to handle—except for the adherence of particles of material upon surfaces with which they may come in contact.

The new fuel, by reason of its sluggishly fluent condition, can be transported from

place to place with simple apparatus, and relatively small expenditure of power. In order to move a column or stream of the fuel through a conveyor conduit of very considerable length, it is only necessary to apply pressure to the fuel constituting a short length of the column and the entire column will be moved along even though there are bends in the conduit and rises to considerable elevations.

The new fuel also lessens the difficulty incident to obtaining quick and complete combustion. When pulverized coal is fed into a furnace and ignited, it is essential to produce an intimate mixture of the coal particles and the air needed to supply the oxygen for combustion. Under some conditions the new fuel may be utilized in such a way that this operation is simplified by the fact that the fuel itself carries a substantial amount of air in intimate admixture with the coal particles.

As an illustration of the manner in which the new fuel may be produced, there is shown in the accompanying drawing in sectional elevation a preferred form of apparatus for this purpose. This apparatus includes a cylindrical casing 10 provided at one end with a supporting foot 11 and connected at the other end to a standard 12, having a cylindrical bore of the same diameter as the interior of the casing. Above the bore is a hopper 13 of any suitable shape and capacity provided with a damper or other form of controlling device 14 by which the discharge of pulverized coal from the hopper may be regulated. Extending through the casing 10 and the bore of the standard 12 is a screw conveyor 15, the shaft 16 of which projects through a suitable bushing 17 which also serves as a closure for the outer end of the bore. The shaft is continued through a bearing 18 which constitutes the main support for the shaft, and its end is connected to an electric motor 19 or other source of power, the connection preferably being in the form of a flexible coupling 20 of any suitable type.

The pitch of the screw conveyor 15 may be made to decrease from the end at which coal is supplied to the end from which it is discharged, the purpose of this arrangement being to compress the pulverized coal as it approaches the discharge end of the conveyor, so that the coal will act as a seal to prevent the air that is introduced as the coal leaves the conveyor from flowing through the casing toward the hopper and aerating the coal before it has been discharged from the conveyor.

For the purpose of introducing air into the coal, there is attached at the forward end of casing 10 an annular casting 21, the lower portion of which is provided with a semi-circular passage 22 substantially con-

centric with the bore of the casting and having its ends brought out to the exterior of the casting, preferably at diametrically opposite points. One end of the passage may be closed by a plug, while into the other end there is screwed one end of a pipe 23 leading to a tank 24 in which the air that is to be injected into the coal may be compressed by a suitable compressor 25 which may be driven by the motor 19 that drives the screw conveyor, the connection between the motor and the compressor preferably being in the form of a flexible coupling 26 of any suitable type. The tank 24 may be provided with a pressure gauge 27, and a suitable regulating valve 28 should be inserted in the pipe 23 to control the amount of air supplied to the coal.

For the purpose of introducing air into the pulverized coal, there is provided a series of forwardly directed ports 29 between the passage 22 and the interior of the casting. Preferably the central ports of the series should be of somewhat greater diameter than the end ports, as it has been found in practice that better results can be obtained with such an arrangement. It has also been found that it is an advantage to introduce the air into the bottom of the column of coal as the material in this region has a greater density as it is delivered from the conveyor than the material in the upper portions of the column. The ports 29, however, need not be limited to the particular number or arrangement described and may extend over a greater or lesser arc, or may even be arranged around the entire circle. They should also be located at a distance from the end of the screw conveyor determined with reference to certain other features of the installation. As the distance through which the coal is to be conveyed increases, there should be a greater packing or sealing effect behind the jets in order that the higher pressure air which is necessary for such increased distances should be forced into the coal and be prevented from flowing through the screw conveyor toward the hopper. This result may be obtained by locating the ports at a greater distance from the end of the screw conveyor.

Attached to the front face of the annular casting 21 is a tapering casing or chamber 30 to the outer end of which is connected a pipe 31 through which the fluent fuel may be distributed to suitable branch conduits through which it may be carried to the points where it is to be utilized. The main conduit 31 may be brought back to the supply hopper to return any surplus fuel not carried out through the branch conduits. The length and taper of the casing 30 and the relation between the diameter of the screw conveyor and that of the distributing pipe 31 depend upon a number of factors,

such for instance as the character of material, the distance to which it is to be conveyed, its velocity and volume.

In the operation of the apparatus described above, the hopper 13 is filled with pulverized coal and by means of the damper 14 the flow of coal to the screw conveyor 15 may be controlled. While the coal is being fed by the screw conveyor, the compressor 25 is in operation to maintain the air which is to be supplied to the coal under the required degree of pressure in tank 24. The air flows from this tank and is discharged through the ports 29 where it becomes thoroughly intermingled with the pulverized coal as the latter leaves the end of the screw conveyor. Owing to the packing action produced at the discharge end of the conveyor or immediately beyond it, the air will be prevented from passing through the casing to the hopper, so that the coal will not be aerated until after it has been discharged from the conveyor.

The quantity and pressure of the air may be regulated by means of the valve to the proper amount to produce the required fluency of the coal. Good results are obtained when the pressure on the air and the size and number of the air ports are such that air enters the conduit to the extent of about six or eight times, by volume, the amount of coal passing the ports. When the fuel is discharged from the conveying conduit into a receptacle which is open to the atmosphere, much of the air escapes gradually from the fuel so that the fuel collecting in the receptacle would ultimately consist of coal greatly in excess of air by volume.

On account of the tendency of the coal to pack when it is not aerated, the supply of air should be turned on before the screw conveyor is started into operation; for otherwise, the coal which is fed beyond the discharge end of the screw conveyor might become sufficiently packed to prevent it from being conveyed through the system.

The air which is supplied to the coal as the latter leaves the screw conveyor will be so thoroughly intermingled with the pulverized coal as to form a sluggishly fluent mass, and the screw conveyor, though of very short length compared to the length of the conveying conduit exerts continuous mechanical pressure on the entire column of fuel throughout the length of the conduit. By reason of this continually applied mechanical pressure and the fluent condition of the fuel, the latter will be moved along through the conveyor conduit throughout the length of the conduit even though the

conduit be of great length and have in it stretches which rise to substantial elevations. At the desired points in the conduit branch conduits lead to the points of use of the fuel and each of these branch conduits may be controlled by diverting or distributing valves. The semi-fluid or sluggishly fluid character of the fuel thus permits of the use of a conveying system which is vastly more simple than those forms of conveying apparatus heretofore commonly employed, and this simple form of conveying apparatus is specially desirable in that it contains no moving parts whatever beyond the point of application of the mechanical pressure for forwarding the column of fuel. At the points of use of the fuel where it is delivered from the conveyor system, the fuel retains its fluent condition and may be utilized the more readily for that reason. If it is caught in a receptacle as it flows from the conveyor system, it will settle slowly but there will be a considerable interval of time before this settling action is appreciable.

I claim:

1. A fuel in a sluggishly fluent state consisting of finely divided coal and air in intimate admixture, the air filling the interstices between the particles of coal and thus giving to the mass its fluent state.

2. A fuel in a sluggishly fluent state consisting of an intimate mixture of finely divided coal and air at a pressure in excess of atmospheric, the air filling the interstices between the particles of coal and giving the fuel its fluent state.

3. A fuel in a sluggishly fluent state consisting of finely divided coal and air filling the interstices between the particles of coal, the fuel being formed by injecting air into the body of finely divided coal.

4. A fuel in a sluggishly fluent state consisting of finely divided coal and air filling the interstices between the particles of coal, the fuel being formed by injecting from four to ten unit volumes of air into one unit volume of finely divided coal.

5. A fuel in a sluggishly fluent state consisting of finely divided coal and air filling the interstices between the particles of coal, the fuel being formed by injecting approximately six unit volumes of air into one unit volume of the finely divided coal.

6. A fuel consisting of a body of finely divided coal having the interstices between the particles filled with air at a pressure greater than atmospheric pressure.

In testimony whereof I affix my signature.

ALONZO G. KINYON.
